UNITED STATES PATENT OFFICE

137,284

DESIGN FOR A COIN DISPENSING DEVICE

Daniel D. Kilcup, Portland, Oreg.

Application September 22, 1943, Serial No. 111,183

Term of patent 14 years

To all whom it may concern:

Be it known that I, Daniel D. Kilcup, a citizen of the United States, residing at Portland, in the county of Multnomah and State of Oregon, have invented a new, original, and ornamental Design for a Coin Dispensing Device, of which the following is a specification, reference being had to the accompanying drawing, forming a part thereof.

In the drawing:

I claim:

The ornamental design for a coin dispensing device, as shown.

DANIEL D. KILCUP.
